BATTERY TERMINAL CLAMP

George F. Berkshier and Carl H. Schmidgall,
Peoria, Ill.

Application August 23, 1930. Serial No. 477,360

6 Claims. (Cl. 173—259)

This invention pertains to battery terminal-post clamps, being of a type applicable to the terminal posts of storage batteries.

The object of the invention is to provide a clamp 5 of a form having a jaw or jaws adapted to and made to bite into the lead terminal post to secure a perfect electrical connection and a permanent rigid securing means for such clamp.

In addition to the object named the invention 10 lies in providing a clamp of a novel form that is simple, that will not get out of order, or become loosened, and that will furnish a very positive and stable connection.

The appended drawing forming part hereof illustrates the invention which, however, is subject to slight changes as may be considered as lying within the scope of the appended claims.

Figure 1 is an elevation of a part of a battery of the secondary or storage type, for example, together with a terminal post, showing the clamp of our invention in connection with the latter.

Figure 2 is a plan of the clamp and the terminal post of a battery showing a lever of the clamp in open position.

Figure 3 is a vertical section of part of the body of the clamp and a part of a jaw in section.

Figure 4 is a front elevation of a jaw, and

Figure 5 is an enlarged section of the clamp in elevation shown mounted on a terminal post.

As is well known, it is difficult to maintain the terminal posts of a storage battery, and especially the positive post thereof, free from corrosion. The corrosive action coupled with a clamp of faulty construction and faulty attaching parts 35 make for difficulties extremely numerous which has occasioned such a device as is now to be described.

In the figures of the drawing the numeral 1 designates part of a secondary or storage battery, and 2 the terminal post thereof.

The clamp of our invention includes a ring 3 which may have any usual tubular part 3' to receive a conductor 3'', for example. It also has an opening 4 through its wall at diametrically opposite positions, said ring having a bore larger than the diameter of the post 2 measured at any point thereon. Within the ring are two jaws 5 of arcuate form as viewed in plan, each having a lug 5' extending from its outer or convex side through one of the openings 4, said lugs having position between the ends of such jaws or substantially at the middle thereof, and said lugs at their free ends lie outside the ring 3 and each receives a cotter 6, for example, by which the jaws are maintained in connected relation with said

ring. Said lugs are somewhat less in diameter than the openings 4 so that free lateral or tipping movement of the jaws is permitted as will be understood presently.

The concave faces of the jaws are opposed to each other and at the lower edge of each is a sharp edge as 7 adapted to "bite" into the soft metal of the terminal post 2, said edge being created in any suitable manner, as to type, the whole object thereof being that a firm and positive bite on the post may be realized. Extending from one side of each jaw, or that side that may be considered its top, is an arm 8, one of them having pivoted thereto a lever 9, the other arm being longer and having a face thereof lying opposite the first arm disposed at an angle, as 10, either as in Figure 1 or as in Figure 5, the lever having an opening 11 through which the said arm having said angled face may extend.

In practice the ring 3 is placed over the post 2 as shown, the jaws 5 meeting the post where the diameter of the latter is about equal to the distance between said jaws, the edges 7 being then in position to be forced into said post. Now, upon closing down the previously raised lever 9 so that the arm having the face 10 enters the hole 11 of the former the two arms 8 will be moved further apart as the lever within the hole 11 thereof moves down the inclined face 10. This action tilts the jaws within the openings 4 of the ring and forces their cutting edges 7 into the metal of the post 2, thereby maintaining them and forming a most positive electrical connection as well as resulting in holding the clamp firmly in place.

The lever may be retained in its relation to the arms 8 by providing a hole 5² to receive a cotter 5³, for example, Figure 1. Other means may, however, be provided for the purpose, if desired.

While the clamp has been described in detail as a preferred form it is to be understood that changes may be made in construction so long as the clamping action is realized with its attendant advantages.

We claim:

1. In combination with the terminal post of an electric battery, a clamp including a ring adapted to encircle the post, a jaw at each of two opposite sides of the ring, one of them being pivoted to said ring including an arm, said jaws adapted to engage opposite surfaces of the post, and a member mounted on one of the named elements adapted to engage the named arm and

therethrough move both jaws toward each other in clamped engagement with the post.

2. In combination with the terminal post of a battery, a clamp including a ring adapted to encircle said post and spaced therefrom, a pair of jaws interposed between the ring and post, one of said jaws being pivoted on said ring and free to rock with respect to it, and means to rock the jaws into gripping engagement with the post.

3. In combination with the terminal post of a battery, a clamp including a ring adapted to encircle the post and spaced therefrom, a pair of jaws on the ring adapted to engage opposite sides of the post, one of them being pivoted to said ring and including an arm and means pivoted on the structure adapted to engage the arm and move the jaws into gripping engagement with the post.

4. In combination with the terminal post of a battery, a clamp including a ring to encircle the post and spaced therefrom, a jaw between the ring and post at one side of the latter, a second jaw between the said ring and said post at the other side of the latter, said second jaw being loosely carried by said ring, means to move the jaws into gripping engagement with

the post, and other means for securing the ring and the second named jaw relatively.

5. In combination with the terminal post of a battery, a clamp including a ring adapted to encircle said post in spaced relation thereto, a pair of jaws interposed between the ring and post at opposite sides of the latter and pivotally mounted on said ring, each of the jaws having a portion adapted to bite into the post and including an arm, the biting portions and the arms of the jaws lying at opposite sides of the pivots, and means pivotally mounted on one of the arms and adapted to engage the other arm for spreading the arms and closing both jaws to close the jaws upon and hold them in engagement with said post.

6. A clamp for the purpose named comprising a ring, a pair of oppositely disposed jaws within the ring mounted thereon and free to tilt and each having a gripping edge one facing the other, each jaw including an extension, one of them having an inclined face, and a member adapted to engage the extensions and slide upon said face adapted to separate said extensions for moving the gripping edges of the jaws toward each other.
